UNITED STATES PATENT OFFICE.

MARTIN G. MOCK AND WALTER S. MAYWOOD, OF MUNCIE, INDIANA.

SHOW-WINDOW VENTILATOR.

SPECIFICATION forming part of Letters Patent No. 331,077, dated November 24, 1885.

Application filed June 21, 1883. Renewed October 10, 1885. Serial No. 179,532. (No model.)

To all whom it may concern:

Be it known that we, MARTIN G. MOCK and WALTER S. MAYWOOD, citizens of the United States, residing at Muncie, in the county of Delaware and State of Indiana, have invented 5 a new and useful Improvement in Show-Window Ventilators, of which the following is a specification.

Our invention relates to improvements in 10 show-window ventilators; and the objects of our improvements are to provide a cheap and simple method and apparatus for ventilating inclosed windows. We attain these objects by the mechanism illustrated by the accompanying drawings, in which—

Figure 1 is a perspective view of our invention with a part broken away. Fig. 2 is a vertical section of the same, and Fig. 3 is a view looking down on the bottom of our invention.

20 Similar letters refer to similar parts throughout the several views.

Our invention consists in providing air-flues at the bottom of a window, with a hinged lid over the upper end of the same, operated by a 25 cord or wire, and making suitable openings at the top of the said window.

On the drawings, A represents the frame of the window, B the end glass, and B' the front glass. The flues a are attached at their upper 30 ends to the floor c'', and hang perpendicular near the sides of the frame A, as shown in Figs. 1 and 2. The said flues a are made of wood or iron, or partly of each, being curved outward at the bottom, so as to catch the inward current of air more freely, all as shown 35 in Figs. 1 and 2. In windows that are not provided with open or grated fronts D the lower

end of the flue a is passed through and secured to the front, as shown at a'' in Fig. 1. The lids b are hinged around the outer edge of the bottom c'' by hinges b', and they are connected together by staples i i at their ends, as shown in Fig. 3, so that when one is raised it raises the other accordingly. A cord or wire, e, is attached to one of the lids, and passes up over 45 the hooks e', then down sufficiently to be easily reached to operate the lids at will. A false bottom, c, is placed on the bottom c'', resting on the bars c', so that goods may be placed on the said bottom c without interfering with 50 the ventilating mechanism. The air draws in through the flues a a', passes up along the glass and out at the openings f, thus making the air inside the window uniform in temperature with that outside, preventing the accumulation of frost or sweat on the said glass.

In warm or dusty weather the lids may be let down, if desired.

Having thus described our invention, we claim the following and desire to secure the 60 same by Letters Patent:

The hinged lids b and the staples i, which connect them, in order that all of said lids may be raised and lowered together, in combination with the cord e, attached to one of said 65 lids, the bottom c, false bottom c', and showcase having inlet-flues a at the bottom and outlet-flues f at the top, substantially as set forth.

M. G. MOCK.

WALTER S. MAYWOOD.
